WALTER SCHAFFER, OF BERLIN, GERMANY, ASSIGNOR TO TELEFUNKEN GESELLSCHAFT FÜR DRAHTLOSE TELEGRAPHIE MIT BESCHRANKTER HAFTUNG, OF BERLIN, GERMANY, A CORPORATION OF GERMANY

METHOD AND ARRANGEMENT FOR DIMINISHING NOISE IN VACUUM TUBES

Original application filed October 28, 1924, Serial No. 746,268, now Patent No. 1,765,542, dated June 24, 1930, and in Germany December 18, 1923. Divided and this application filed July 21, 1927. Serial No. 207,417.

This invention relates to method and apparatus for diminishing and eliminating the note caused by the use of alternating current for heating the cathode of thermionic tubes and is for the same purpose as the method and means set forth in my copending application Serial No. 746,268 filed Oct. 28, 1924, Patent No. 1,765,542, June 24, 1930, of which this is a divisional application.

10 The object of this invention is to provide an arrangement whereby the note caused by the alternating cathode heating current is compensated or eliminated. This is accomplished by using an anode current derived 15 from an alternating current of the same frequency as the cathode heating current.

Another object of the invention is to provide means whereby the relative amplitude and the phase relation of the direct current 20 anode current and the grid cathode current can be regulated, in such a manner that the note caused by the alternating current in the grid cathode circuit can be totally eliminated.

25 Other objects will be apparent from the following description and claims when taken with the accompanying drawing in which:—

The single figure is a schematic representation illustrating my invention.

30 Electron tubes whose cathodes are heated by alternating current ordinarily cause a tone of the alternating current frequency and also of double the frequency in the output circuit. It is all the same whether the 35 electron tube is used as an amplifier or as an oscillation generator. In the latter case the generated oscillation is modulated by the tones caused by the heating current. Means for diminishing these tones caused

40 by the heating current are known. A very suitable arrangement is, for instance, to arrange an ohmic resistance in parallel to the heating filament and to use the middle of this resistance as the "K"-point, that is, the

45 connection contact of the grid circuit and of the anode circuit. That component of the heating current note which has the same frequency as the heating current can be completely eliminated by this connection.

50 On the other hand, a heating current note

of the double frequency remains. This note is based upon two causes: Firstly, the heating of the filament and consequently the electron emission slightly pulsates in the rhythm of double the heating current frequency, even when an alternating current of as high as 500 periods per second is employed. Secondly, the potential of the filament with respect to the grid is varied with the double frequency, as the two halves of the filament must be regarded as symmetrical.

55 In case the anode voltage is generated by a rectified alternating current, the anode current itself also contains a component of the double frequency of the employed rectified alternating current, and this frequency is particularly strong when a two phase alternating current is led through a two-parted rectifier. So the anode current brings in the same disturbing note as the heating current, if the anode alternating current and the heating current have the same frequency. The components caused by the anode current and heating current will 60 strengthen or weaken one another according to the difference of phases of these two currents. This fact is employed by the present invention according to which the phases 65 of the disturbing components caused by the heating voltage and by the anode voltage are compulsively and constantly adjusted during the working of the electron tube, so that the two components act against one another and weaken one another.

70 Referring to the single figure the transmitting tube *a* acts upon the oscillatory circuit *b* which comprises inductance *L* and capacitance *V*. Inductance *L* has a portion connected in the output circuit of tube *a* and also a portion in the input circuit of tube *a* to give the necessary feed back to cause sustained oscillations. The generator *c* acting through the transformer *d* supplies the heating alternating current. The 75 secondary of transformer *d* is connected to the filament of the tube *a* to which the resistance *e* is connected in parallel, and the middle of this resistance is, as known, the "K"-point. The generator *g* produces a 80

two-phased alternating current of the same frequency as that of the heating current generator *c*. This current is transformed by transformer *h* and rectified by the double rectifier *i*. The alternating current generators *c* and *g* are compulsively connected to one another by the coupling *A*, and it is all the same whether they have a common shaft or not. The coupling *A* contains an arrangement by means of which the rotors of both generators can be adjusted to any desired relative angle. The maximum turning angle corresponds to a phase displacement of 360° between the alternating currents of the two generators. Any phase angle between heating current and anode current can be adjusted by means of this arrangement.

The grid-cathode circuit is coupled to the direct current anode circuit, for instance, inductively, in such a way that the alternating current component of the double working frequency which the anode direct current contains, is superimposed on the normal grid direct current or alternating current. Thereby the disturbing component which is brought in by the heating current, is compensated to a certain extent, or more exactly, it is equalled to the component of the anode note. The right phase for which the disturbing note is a minimum so that it will completely disappear at suitable coupling, may be adjusted, as mentioned above, by regulating the variable coupling of the generators.

In this case the anode circuit contains an inductance *m* and the grid circuit an inductance coil *n*. The inductances *m* and *n* are coupled to one another by a variable coupling, the sense of which can be reversed. The condenser *o* bridges over the coupling coil *n* for the high frequency flowing through the grid circuit of the tube transmitter. The arrangement is adjusted in such a way that first the coils *m* and *n* are short-circuited and the phase between the working anode current and the heating current is adjusted to make the disturbing note a minimum by suitably regulating the coupling *A*; then the short-circuit is removed from the coils *m* and *n*, and then the disturbing note is farther diminished or completely eliminated by suitably adjusting the sense of coupling and the coefficient of coupling.

In some cases it may be appropriate to adjust the phases of the disturbing components of the anode current and the grid current only partly by means of the coupling *A* of the generators *g* and *c* by which often only an inaccurate regulation is carried out. For the accurate regulation of the phases, further impedances are inserted in the anode circuit, or grid circuit, by means of which an accurate phase displacement is possible.

This can, for instance, be carried out by connecting a capacity *p* in parallel to the coil *m*, or a capacity *p'* in parallel to coil *n*, and then nearly tuning *p* and *m*, or *p'* and *n*, to the disturbing frequency. The phase regulation is based upon the knowledge that a coupled circuit near to its resonance possesses a phase varying from 0° to 180° together with the capacity. Of course, it is also possible to displace the phases of the two disturbing components by arranging any other resistances in the anode circuit or direct current grid circuit.

In each case the currents are adjusted to that point of phase relationship at which the disturbing note which for instance may be tested by means of an auxiliary detector circuit (not shown) has the least strength.

Having described my invention and the operation thereof I claim:

1. The method of diminishing the alternating current hum from thermionic valves the anode cathode circuit and the cathode heating circuit of which are energized from an alternating current source which comprises, supplying, the cathode heating circuit with alternating current, supplying the anode cathode circuit with current derived from alternating current of the same frequency, roughly adjusting the phase relation of said currents to oppose each other, coupling the direct current anode cathode circuit to the direct current grid cathode circuit, adjusting the magnitude of the two currents to be numerically equal to each other, and finely adjusting the phase relation of said currents to oppose and compensate each other.

2. The method of diminishing the alternating current hum from thermionic valves the anode cathode circuit and the cathode heating circuit of which are operated from an alternating current source which comprises, supplying the cathode heating circuit with alternating current, supplying the anode cathode circuit with current derived from alternating current of the same frequency, adjusting the phase relation of said currents to oppose each other, and coupling the direct current anode cathode circuit to the grid cathode circuit.

3. The method of diminishing the alternating current hum from thermionic valves when the anode cathode circuit and the cathode heating circuit thereof are operated from an alternating current source, which consists of supplying the cathode heating circuit with alternating current, supplying the anode cathode circuit with current derived from alternating current of the same frequency, adjusting the phase relation of said currents to oppose each other, coupling the direct current anode cathode circuit to the grid cathode circuit, and adjusting the mag-

nitude of the two currents to be numerically equal.

4. The method of diminishing the alternating current hum from thermionic valves
 5 the anode cathode circuit and the cathode heating circuit of which are operated from an alternating current source which comprises supplying the cathode heating circuit with alternating current, supplying the
 10 anode cathode circuit with potential obtained by rectifying alternating current of the same frequency, roughly adjusting substantially at their source the phase relation of said currents to oppose each other, coupling the direct current anode cathode circuit to the grid cathode circuit, and adjusting the magnitude of the two currents so that they will be equal to each other.

5. In radio apparatus a thermionic valve
 20 having anode cathode and grid electrodes, a direct current anode cathode circuit, a direct current grid cathode circuit, a source of current for said anode cathode circuit derived from alternating current, a source of
 25 alternating current of the same frequency for heating the cathode of said valve, and means including a coupling between said direct current circuits for adjusting the phase relation and the relative magnitude of said
 30 currents.

6. In radio apparatus a thermionic valve having anode cathode and grid electrodes, a

direct current anode cathode circuit, a direct current grid cathode circuit, means for excluding radio frequency currents from said direct current anode cathode circuit, a source of current for said anode cathode circuit derived from alternating current, a source of alternating current of the same frequency for heating the cathode of said valve, a tuned impedance in said direct current anode cathode circuit, a tuned impedance in said direct current grid cathode circuit variably coupled to said first named impedance, and means for excluding radio frequency current from the impedance in said direct current grid cathode circuit.

7. An arrangement for supplying anode potential, and heating current to the cathode of a thermionic valve having high frequency input and output circuits including, a source of alternating current for the cathode heating circuit, a circuit for supplying rectified alternating current to the anode circuit from an alternating current source, and coupling means between the input circuit and the anode supply circuit for producing a hum frequency voltage in said input circuit and means for adjusting the phase and amplitude of said voltage to substantially reduce the hum caused by alternating currents.
